UNITED STATES PATENT OFFICE.

JEREMIAH KELLER, OF CHICAGO, ILLINOIS, ASSIGNOR TO JOSEPH E. ROSENFELD, OF OMAHA, NEBRASKA.

ROTARY VALVE FOR INTERNAL-COMBUSTION ENGINES.

1,406,986.

Specification of Letters Patent. Patented Feb. 21, 1922.

Application filed March 17, 1919. Serial No. 283,193.

To all whom it may concern:

Be it known that I, JEREMIAH KELLER, a citizen of the United States, residing at Chicago, county of Cook, and State of Illinois, have invented certain new and useful Improvements in Rotary Valves for Internal-Combustion Engines, of which the following is a specification.

The present invention has to do with improvements in rotary valves for internal combustion engines and has particular reference to improvements in poppet valves embodying the rotary feature. These poppet valves are normally seated under spring pressure and they are opened by lifting them against such spring pressure. The peripheral portion of the valve is generally beveled to seat evenly against a beveled seat. Owing to wear in the operation of the valve, and also owing to the high temperatures at which it operates, it is found desirable to cause the valve to rotate during the successive operations.

Owing to the high speed at which these valves operate, it is necessary to provide a very positive form of rotating mechanism and one which will operate positively at high speed. One of the objects of this invention is to provide a rotating device which 30 will conform very successfully to this requirement.

The springs which are used for reseating the valve are generally very stiff and exert a very large seating force. Consequently, it is 35 desirable to so construct the rotating mechanism that the friction or resistance generated by the spring will not interfere with the rotation of the valve itself. Therefore, another object of the invention is to so construct the valve and rotating mechanism that the force of the spring will not be transmitted through the rotating devices, but will be taken care of independently thereof.

Another object is to provide a mechanism 45 of this type which shall be simple and easily constructed from a comparatively small number of parts and at low cost.

Other objects and uses of the invention 50 will appear from a detailed description of the same, which consists in the features of construction and combinations of parts hereinafter described and claimed.

In the drawings: Figure 1 shows a vertical fragmentary section through certain of the 55 passages of an internal combustion engine, having applied thereto a valve and rotating

mechanism embodying the features of the present invention. In Fig. 1 the valve is shown in its closed position.

Fig. 2 shows a view similar to that of Fig. 60 1, with the exception that the valve is in open position.

Fig. 3 shows a bottom end view of the rotating mechanism.

Fig. 4 shows a longitudinal section 65 through the valve and rotating mechanism on considerably enlarged scale as compared to the previous figures.

Fig. 5 shows an enlarged cross section 70 through the spring-cup.

Fig. 6 shows a bottom view corresponding to Fig. 5.

Fig. 7 shows a side view of the plug which closes the lower end of the spring-cup.

Fig. 8 is a view similar to Fig. 7, but is 75 taken at right angles thereto.

Fig. 9 is a section taken on line 9—9 of Fig. 4 looking in the direction of the arrows.

Fig. 10 is a section taken on the line 10—10 of Fig. 4 looking in the direction of the 80 arrows.

Fig. 11 is a section taken on the line 11—11 of Fig. 4 looking in the direction of the arrows; and,

Fig. 12 is a side view of one of the clutch 85 elements.

For purposes of convenience in illustration and for a better understanding of the invention, I have shown the valve as being applied to an engine 13 having a gas passage 90 14 and another gas passage 15 between which the flow of gas is to be controlled. The valve itself is designated by the numeral 16. It is formed or fastened to the upper end of the stem 17, which stem extends 95 down through and finds a reciprocating bearing in a neck portion 18.

Ordinarily the reciprocation of the valve is secured by a finger or a cam pressing upwards against the lower end of the stem. 100 In the present case I have provided means whereby the stem will be periodically rotated during its movement. I will now describe the same in detail.

The bearing-sleeve 18 is shown as projecting 105 downwardly in a continuation 19 so as to give additional bearing and support to the valve-stem. A collar 20 surrounds the extension 19 and has a flange 21 which seats against the partition wall 22 of the engine. 110 This collar has a downwardly extending sleeve 23, the detailed construction of which

is well shown in Figs. 1 and 2. It is provided with a pair of oppositely located slots 24 and 25, only the slot 24 appearing in Figs. 1 and 2. Another sleeve 26 surrounds the lower portions of the stem 17, being spaced from said stem a sufficient distance so that its arms 27 and 28 may work within the slots 24 and 25. Only the arm 27 appears in Figs. 1 and 2.

10 The arms 27 and 28 are in reality formed by a pair of slots cut in the sleeve 26, which slots are complementary to the slots 24 and 25. All of the slots are cut at an angle with respect to the axial direction of the 15 device, so that while moving the two sleeves 23 and 26 with respect to each other, they will be caused to rotate through a desired angle. It is desired to provide means for communicating this rotation to stem 17 in 20 such a way and in such manner as to insure the proper rotation of the valve.

The lower end of the sleeve 26 carries a flange 29 which works within a clutch-cup 30. Said clutch-cup is provided with a 25 downwardly depending collar 31 which is secured to the lower end of the stem 17 by a pin 32. In the particular construction illustrated, a bushing 33 has been shown between the collar 31 and the lower end of 30 the valve stem, but in many cases this bushing may be eliminated and the parts brought directly together.

Flange 29 is provided with a number of cam slots 34, as best shown in Fig. 10, each of 35 which has an abrupt face and a gradual face. The rollers or balls 35 are set into these cam slots 34 so that upon turning the flange 29 of the sleeve 26 in counter clockwise direction, as shown in Fig. 10, the balls or 40 rollers will rock and cause the clutch-cup 30 to also rotate, which rotation will be communicated to the valve stem.

In order to insure a proper seating of the rollers during the periodical operation of the 45 device at high speed, I have shown the springs 36 which press against the rollers and tend to force them into locking engagement between the parts at all times. A spring washer 37 serves to retain the 50 rollers 35 and springs 36 in position within the friction cup.

The main spring 38 tends to force the valve stem down for the purpose of seating the valve. Ordinarily, this spring communicates its force directly to the valve stem or to some element directly connected therewith. In the present case I have provided a spring-cup 39 comprising a flanged portion 40 and a collar 41, which spring-cup 55 surrounds or covers over the friction clutch. This cup is provided with an upstanding flange 42 around which is seated a washer 43 against which the lower end of the main spring 38 finds a bearing. By reason of 60 the configuration of the spring-cup 39, a

space or clearance 44 is provided beneath the spring 43 into which may be entered the forks of a valve lifting tool in order to remove the spring pressure from the valve when desired.

70 The upper end of the spring presses directly against the flange 21, or against a washer 45 seated thereagainst.

A cap 46, the detailed construction of which is shown in Figs. 7 and 8, serves to 75 close the lower end of the spring-cup. This cap is generally circular in form and has an upstanding central lug 47 which seats into the lower end of the spring-cup. This lug is provided with a mutilated bevel comprising 80 the beveled portions 48 and 49, each occupying practically 90° of circumference, in combination with a pair of mutilated or straight sections 50 and 51, each of which also occupies approximately 90° of circumference. 85 The lower portion of the spring-cup is so formed, as shown in Fig. 5, that the cap may be set into it, after which the cap may be rotated a quarter of a turn to completely lock it.

90 A spring washer 52 is seated between the lower face of the clutch-cup and the cap, so that a certain amount of friction is at all times generated between these parts. This will be readily understood from an examination of Fig. 4.

During the lifting operation the lifting force is communicated directly to the lower face of the cap 46. From there it is transmitted to the valve stem 17 through the 100 medium of the spring washer 52, and is independently transmitted to the main spring 38 by way of the spring-cup and washer 43. It is thus observed that at no time does the force necessary to compress the main spring 105 have to be transmitted either to or through the valve stem, so that the friction created by the main spring itself does not have to be overcome in order to rotate the valve stem.

110 In the ordinary operation of this device, upon lifting the spring-cup the same will be held against rotation by the friction of the main spring, the upper end of said spring being in contact with a stationary 115 part 45. The friction created by the washer 52 between the clutch-cup 30 and the cap 46 will be sufficient to retain the valve-stem against rotation on the up-stroke. During this up-stroke, the sleeve 26 will be rotated 120 in a backward direction by reason of its engagement with the sleeve 20, which latter sleeve is held against rotation by its frictional engagement with the stationary part. On the down-stroke, the sleeve 26 will be 125 rotated forward through the angle corresponding to the slots 24 and 25, which forward rotation will be communicated to the clutch-cup 30, through the medium of the rollers 35. The rotation of the clutch-cup 130

will, of course, be transmitted to the valve stem, which will thus be rotated through the desired angle on the down-stroke.

By the use of a construction in which the 5 rotation of the valve takes place on the down-stroke as distinguished from rotation on the up-stroke, it is possible to have the valve in rotation at the instant it comes into contact with the seat, so that more or less 10 of a grinding action is secured. This results in a more perfect seating at each operation and also serves to keep the valve and seat always in perfect condition. In 15 fact the action is such as to polish the valve and seat, and maintain them in such condition. This action is enhanced by the further fact that the arrangement permits the valve to over-ride in its rotary motion, continuing its rotation beyond the time when 20 the rotating tendency of the clutch has ceased. The use of a friction clutch in turn assists this over-riding tendency since it is possible for the valve to continue its motion much easier with this type of drive 25 than is the case when using a ratchet or other similar device.

While I have herein shown and described only a single embodiment of the features of my invention, still I wish it understood that 30 I do not limit myself to said embodiment except as I may do so in the claims.

I claim:

1. In a device of the class described, the combination with a valve having a down- 35 wardly depending stem and a stationary member through which said stem operates, of a pair of cooperating sleeves surrounding the stem and having complementary engaging angular projections whereby relative longitudinal movement between said 40 sleeves results in their relative angular movement, one of said sleeves being in engagement with a stationary part, a clutch flange on the lower end of the other sleeve, 45 said clutch flange having a plurality of cam slots, a clutch-cup surrounding said flange, a connection between said cup and the lower end of the valve stem, clutch rollers between the clutch-cup and the clutch flange, springs 50 normally pressing said rollers into locking engagement between the parts, a spring-cup surrounding the clutch-cup and freely movable with respect thereto, a cap closing the lower end of the spring-cup, a spring washer 55 between the clutch-cup and said cap, and a main spring surrounding the parts and occupying a position between the spring-cup and a stationary part, whereby lifting pressure applied to the cap is transmitted 60 through the spring-cup directly to the main spring, and also is transmitted directly to the lower end of the valve stem independently, substantially as described.

2. In a device of the class described, the combination with a valve having a stem 65 working within a stationary part, of a clutch-cup secured to the lower end of the stem, a clutch-flange in said cup having a plurality of cam notches in its periphery, clutch rollers in said notches, springs normally forcing said rollers into locking engagement between the parts, means for periodically rocking the clutch-flange back and forth for the purpose of intermittently rotating the clutch-cup, a spring-cup surrounding the clutch-cup and independent thereof, a cap closing the lower end of the spring-cup and a main spring surrounding the stem and located between the spring-cup 70 and the stationary part whereby pressure 75 lifting forces exerted on the cap are transmitted directly to the main spring through the spring-cup and whereby said lifting forces are also transmitted directly and independently to the lower end of the valve 80 stem, substantially as described.

3. In a device of the class described, the combination with a poppet valve and a stationary part wherein the same operates, said poppet valve having a valve stem, of a friction clutch interposed between said valve stem and another part against which said friction clutch may react, means for intermittently operating said friction-clutch for the purpose of intermittently rotating the valve stem, 90 a spring-cup surrounding the friction clutch, a cap closing said spring-cup and a main spring interposed between the spring-cup and the stationary part, whereby lifting forces on the cap are transmitted directly to 100 the main spring through the spring-cup and are independently transmitted to the valve stem, substantially as described.

4. In a device of the class described, the combination with a poppet valve and a stationary part wherein the same operates, said poppet valve having a valve stem, of a friction clutch comprising a clutch flange and a clutch-cup, clutch rollers between the clutch flange and cup, a connection between 105 the clutch-cup and valve stem, a pair of sleeves slidably and rotatably mounted with respect to each other and surrounding the valve stem, complementary cam surfaces on said sleeves for producing a relative rotation between the sleeves when they are moved relatively in an axial direction, a spring-cup surrounding the friction clutch, a closure therefor and a main spring between the spring-cup and the stationary 110 part whereby lifting forces applied to said closure are transmitted directly to said main spring and independently to the valve stem, 115 substantially as described.

JEREMIAH KELLER.
